US00D530482S

(12) **United States Design Patent** (10) **Patent No.:** **US D530,482 S**
(45) **Date of Patent:** **** Oct. 24, 2006**

(54) **FOOD PRODUCT**

(75) Inventors: **Decai Zhang**, Battle Creek, MI (US); **Hillis Orvin Kauffman**, Battle Creek, MI (US); **Douglas Drogosh**, Galesburg, MI (US); **Mark Holdridge**, Richland, MI (US)

(73) Assignee: **Kellogg Company**, Battle Creek, MI (US)

(**) Term: **14 Years**

(21) Appl. No.: **29/256,077**

(22) Filed: **Mar. 15, 2006**

Related U.S. Application Data

(62) Division of application No. 29/205,923, filed on May 21, 2004, now Pat. No. Des. 522,211.

(51) **LOC (8) Cl.** **01-01**

(52) **U.S. Cl.** **D1/125; D1/129**

(58) **Field of Classification Search** D1/100-30, D1/199; D11/6, 13, 15, 17-8, 20; 426/27, 426/91, 93, 101, 103-4, 138, 144, 272, 280, 426/390-1, 412, 500, 512, 514, 565, 571, 426/94, 249, 282-284, 516, 549; D21/672; 220/566; 264/75; 425/135, 191, 288, 319, 425/334, 381, 382.3

See application file for complete search history.

CLAIM

We claim the ornamental design for a food product, as shown.

DESCRIPTION

FIG. 1 is a perspective view of the food product with a right-handed twist

FIG. 2 is a top view thereof;

FIG. 3 is a right side view thereof;

FIG. 4 is a bottom view thereof;

FIG. 5 is a first end view thereof;

FIG. 6 is a second end view thereof; and

FIG. 7 is a left side view thereof.

FIG. 8 is a perspective view of the food product with a left-handed twist;

FIG. 9 is a top view thereof;

FIG. 10 is a right side view thereof;

FIG. 11 is a bottom view thereof;

FIG. 12 is a first end view thereof;

FIG. 13 is a second end view thereof; and,

FIG. 14 is a left side view thereof.
